ADJUSTABLE SPOOL MOUNTING FOR WIRE
SPOOLER MECHANISM

William D. Pierson and Raymond E. Walsh, Waterbury, Conn., assignors to The Waterbury Farrel Foundry & Machine Company, Waterbury, Conn., a corporation of Connecticut

Application May 25, 1936, Serial No. 81,656

6 Claims. (Cl. 242—25)

This invention relates to wire-spooling machines, and more particularly to an improvement in the means for adjustably supporting the spool upon which the wire is wound as it is received from a wiredrawing machine.

In machines of the above nature, the wire-receiving spool is usually supported by a pair of cylindrical center spindles which are disposed within the opposite ends of the bore of the spool. Such spools are usually made of metal or wood, and comprise a pair of end circular flanges between which is a central hollow barrel. The diameter of the central barrel is apt to vary an appreciable amount when manufactured, and also wears larger during continued use. Consequently, a loose fit is often produced on the driving spindle causing rattling, vibration, and noisy operation of the spool, which may result in breakage of the wire, particularly when small sizes are being spooled. On the other hand, if the size of the bore of the spool barrel is too small, the bore must be reamed out to the correct standard diameter,—a time-consuming and expensive operation.

By means of the present invention, the above and other disadvantages have been overcome.

Accordingly, one object of this invention is to provide a pair of self-adjusting tapered plugs adapted to enter the bore at each end of the spool, whereby spools having central bores of various diameters may be accommodated.

Another object is to provide an adjustable spool mounting of the above nature in which the tapered center plugs are spring-pressed.

A further object is to provide a mechanism of the above nature having means to limit the rearward movement of each of the spool plugs for preventing said spool from becoming accidentally detached from its mounting.

A still further object is to provide an adjustable spool mounting of the above nature which will be relatively simple in construction, inexpensive to manufacture, easy to install and manipulate, compact, and very efficient and durable in use.

With these and other objects in view, there have been illustrated in the accompanying drawings two forms in which the invention may be conveniently embodied in practice.

In the drawings:

Fig. 1 is a top plan view of a portion of a spooling machine upon which this invention has been installed.

Fig. 2 is an end view of the same.

Fig. 3 is a longitudinal sectional view through the spool and the supporting means therefor,

the view being taken on the line 3—3 of Fig. 1 and being shown on a somewhat larger scale.

Fig. 4 is a longitudinal section similar to Fig. 3 of a modified form of adjustable spool mounting, the spool being overhung and supported by one bearing only.

Fig. 5 is a fragmentary longitudinal sectional view similar to Fig. 3, but shown on a much larger scale.

Fig. 6 is a similar enlarged sectional view of 10 the modified form shown in Fig. 4.

A spooling mechanism upon which the present invention may be installed is fully disclosed in a prior patent to Pierson, No. 2,029,832, issued February 4, 1936.

Referring now to the drawings in which like reference numerals denote corresponding parts throughout the several views, the numeral 10 indicates a wire which is delivered to the spooler from a wiredrawing machine, not shown, and which is guided into a spool 11 by means of a pair of angular fingers 12 between which it is threaded. The guide fingers 12 are adapted to be reciprocated longitudinally above one side of the spool 11 by suitable means, not shown, to lay 25 the wire thereon in even layers. The spool 11 is caused to rapidly rotate by an endless belt 13 which is in driving engagement with the wire on the spool 11 and passes around the pulleys 14 and 15. As herein disclosed, the pulley 14 is 30 power-driven from a shaft 16, to which it is connected, and the pulley 15 is freely rotatable on a shaft 17 carried by a cradle bracket 18, the latter being swingably mounted on the shaft 16.

In order to move the belt 13 transversely back 35 and forth across the wire on the spool 11, provision is made of a pair of reciprocable belt-shifting members 19.

Spool mounting

The spool 11 is supported by a pair of spring-pressed center spindles 20 and 21 mounted in casings 22 and 23, respectively. The casing 22 is mounted upon a machine frame member 24, and said casing has a base 25 for receiving bolts 45 26 which pass through slots 27 in said base for holding said casing 22 in axially adjustable position with respect to said spool 11.

The other casing 23 is carried by a depending bracket 23a which is slidably mounted upon a 50 stationary supporting shaft 28 located under said casing, and said bracket 23a is adapted to be clamped upon said shaft 28 by means of a manually operated transverse clamp screw 29.

As clearly shown in Figs. 3 and 5, each of the 55

- center spindles 20 and 21 is formed and mounted in an identical manner, and therefore, the same reference characters have been used to indicate the corresponding parts thereof. A pair of opposed tapered heads 30 are rigidly secured on the ends of said spindles 20 and 21, and said heads are adapted to adjustably enter the ends of the center barrel 31 of the spool 11 for securely mounting it therebetween in operating position.
- 10 Behind the heads 30 the center spindles 20 and 21 are reduced in diameter to form sliding bearing portions 32 and outwardly directed shoulders 33. Beyond the bearing portion 32, the spindles 20 and 21 are still further reduced in diameter 15 to form elongated shanks 34 extending outwardly from the shoulders 35. The shanks 34 are herein shown as being threaded at their outer ends to receive nuts 36 but may have collars (not shown) pinned thereon within the spirit and scope of 20 the invention.
- 20 Each of the center spindles 20 and 21 is slidably and non-rotatably supported by a sleeve 37 having a bore 38 surrounding said spindles. Each bore 38 is enlarged in diameter as at 39 to receive the shouldered bearing 32 and terminates in an outer shoulder 40, thus providing a confining space for a compression spring 41 which is adapted to engage the shoulders 35 and 40 to constantly urge the center spindles resiliently against 25 the ends of the spool 11. The movements of the center spindles 20 and 21 toward the spool under the urge of the springs 41 are limited by the striking of the nuts 36 against the outer ends of the sleeves 37. The inner ends of the bores 38 of the sleeves 37 are still further enlarged as 30 at 42 forming shoulders 43 to receive the tapered heads 30 and against which the shoulders 33 of said tapered heads 30 are adapted to engage for limiting the outward movements of the center spindles 20 and 21, and thus preventing said tapered heads from slipping out of the spool bore 31. Each center spindle may be retained against 35 rotation relative to the sleeve 37 by means of a keyway 42a in the bore section 42, which cooperates with a transverse pin 30a extending from 40 the head 30.
- 37 The spindle sleeve 37 is provided with a circular dish-shaped member 44 at its inner or spool end, said member having an annular outer flange 45 extending parallel to the axis of the spindle away from said spool 11. Each dish-like member 44 is provided on its inner face with an annular reduced ring 46 adapted to frictionally engage and drive a pair of end plates 47 formed on the spool 11. If desired, a pin 46a may be provided 50 on one or both rings 46 to engage in sockets 47a in the plates 47 to insure positive rotation of the spool and plates 47 as a unit.
- 55 The end sections 48 of the sleeves 37 are reduced in diameter at 49 to receive the inner ball races 50 of two sets of ball bearings 51. One race 50 engages against a shoulder 52 at the inner end of the portion 49, the other race being disposed adjacent the outer end of said portion 50 against a washer 56 which engages a ring-nut 53 screwed upon a threaded end 54 provided on the rear end of the sleeve 37. An intermediate spacing collar 55 is disposed on the sleeve 37 between the ball races 50.
- 60 The spindle casings 22 and 23 are each provided with inner end plates 57 having central openings 58 therein loosely surrounding the exterior surfaces 48 of the sleeves 37. If desired, an oil retaining ring packing 59 may be provided to seal the space between the plate 57 and

the sleeve 37. Each casing 22, 23 is also provided with an outer annular cover plate 60.

Each cover plate 60 has a cylindrical hollow dome portion 61 thereon forming a housing for the end of the respective center spindle 20, 21. An air vent 62 is provided in the end face of the dome 61. The plates 57 and 60 are securely clamped in position upon the casings 22 and 23 by a plurality of elongated cap screws 63, and said plates engage the exterior ball bearing races 10 64, as clearly shown in Fig. 5.

Operation

In the operation of the first form of the invention, when it is desired to insert a spool 11 between the center spindles 20 and 21, the clamp screw 29 must first be loosened and the bracket 23a slid along the shaft 28 as far as it will go. An empty spool may then be positioned with the tapered end of the center spindle 20 projecting 20 into the right-hand bore 31 of the spool 11, as viewed in Figs. 3 and 5. When in this position, the spindles 20 and 21 will be extended toward each other by the spring 41 from their respective casings 22 and 23 to the extent permitted 25 by the nuts 36. The bracket 23a and the casing 23 will then be slid in the opposite direction along the shaft 28, causing the tapered end 30 of the left-hand center spindle 21 to enter the bore 31 of the spool 11. During this operation, the casing 23 and ring 46 will be pushed firmly against 30 the spool to compress both of the springs 41. While holding the parts in this position, the clamp screw 29 will be tightened to lock the parts in the assembled position shown. It will be understood that the tapered ends of the spindle plugs 20 and 21 accurately center the spool 11 within the limits of the taper, regardless of variations in the diameter of the bore 31 thereof, and due to the provision of the cooperating stop 35 shoulders 33 and 43, the respective plugs 20 and 21 can never be forced completely out of the bore 31 by the lateral pressure of the driving belt 13 on the spool or by the pull on the wire 10 being wound thereon; i. e., while the spool is clamped 40 between the dish-shaped members 44.

Modified overhung spool mounting

In the modified form of the invention shown in Figs. 4 and 6, an overhung spool 70 having a center barrel 71 is mounted between a pair of tapered center sleeve plugs 72 and 73, which in turn are loosely slideable upon a mandrel 74 of the overhanging type, supported in bearings in a single casing 100 located at one end of said spool only. The mandrel 74 is connected to a sleeve shaft 75 which is suitably extended at its rear end 76 into driving connection with a source of power, not shown. A reduced end 77 of the mandrel 74 is inserted into an end opening 78 in the shaft 75, and the two parts 74 and 75 are connected together by a transverse tapered pin 79.

The outer free end 80 of the mandrel 74 is likewise reduced in diameter and has mounted thereon a collar 81 which is adapted to be detachably secured to said free end 80 by a set screw 82. The collar 81 is provided with a bore 83 which is adapted to have a sliding fit upon the hollow shank 84 of the sleeve plug 72. The set screw 80 82 extends through a slot 82a provided in the sleeve plug shank 84 which permits relative axial movement between the sleeve plug 72 and the collar 81, while preventing relative rotative movement therebetween. The outer end of the de- 75

tachable collar 81 is counterbored at 85 for receiving a stop ring 86 riveted or otherwise secured upon the free end of the shank 84 to prevent the sleeve plug 72 becoming disassembled from the collar 81. The other end of the collar 81 is provided with a counterbore 87 having a shoulder 88 and a cavity 89 in which the center plug 72 may slide, said cavity 89 also housing a compression spring 90. The sleeve plug 72 has a shoulder 91 formed in back of its tapered portion 92, and the spring 90 is held between the shoulders 88 and 91 to constantly urge the sleeve plug 72 into the end of the spool barrel 71.

The collar 81 is also provided on its inner end 15 with an enlarged counterbore 81a forming a shoulder 92a against which the shoulder 91 of the sleeve plug 72 will engage to prevent said plug 72 from moving completely out of the spool barrel 71.

20 The spool-driving sleeve shaft 75 is provided with an annular recess 93 surrounding the inner end 77 of the mandrel 74. The inner sleeve plug 73 comprises a short tapered collar or sleeve and is slidably mounted upon the reduced end 77 of the mandrel 74, being pressed to the right, as viewed in Figs. 4 and 6, by a coiled spring 94 located in said recess 93 to constantly urge the inner sleeve plug 73 into the spool barrel 71.

In order to prevent relative rotative movement, 30 while permitting relative axial movement, between the sleeve plug 73 and the mandrel 74, provision is made of a transverse pin 77a secured in the reduced portion 77 of the shaft 75 and projecting into a slot 73a formed in said center plug 73. The shaft 75 is also provided with a dish-shaped end plate 95 which is provided with an annular reduced longitudinal outwardly extending ring 96 adapted to engage one of the end plates 97 and 98 of the spool 70. A driving pin 99 is also provided, extending longitudinally from the boss 96 into an opening provided in the adjacent spool end plate 98, by means of which the spool is drivingly connected to the shaft 75.

The sleeve shaft 75 is journaled in the casing 100 by means of two sets of ball bearings 101 spaced apart by a collar 102 and clamped together between a shoulder 103 on the periphery of the shaft 75 and a ring nut 104. A pair of front and rear end plates 105 and 106 are also provided in this form and said plates are clamped to the casing by a plurality of elongated cap screws 107. An oil retaining ring packing 108 may be provided to seal the space between the plate 105 and the shaft 75. The rear end plate 106 has a rearwardly extended hollow dome portion 108a enclosing the ring nut 104 and may have an oil retaining ring packing 109 between it and the shaft 75 to seal the space therebetween.

Operation of modified form

In the operation of the modified form shown in Figs. 4 and 6, the wire-filled spool 70 may be removed from the mandrel 74 by loosening the set screw 82 and axially sliding the collar assembly 81 therefrom to the right. The tapered sleeve plug 72 will be removed with the collar 81, but does not become separated therefrom due to the stop ring 86. The spool 70 may now be removed from the mandrel 74 by sliding it axially and replaced with 70 an empty spool.

The empty spool will be arranged with the drive pin 99 fitted into its socket, as shown. The collar 81 will then be replaced on the reduced end 80 of the mandrel 74, causing the tapered sleeve plugs 72 and 73 to enter the bore 71 of the spool 70.

This action compresses the springs 90 and 94 and places the sleeve plugs 72 and 73 firmly against the opposite ends of the bore 71, regardless of variations in the diameter of the bore. The set screw 82 will finally be tightened and the machine 5 will then be ready for the operation of winding wire upon the spool 70.

While there have been disclosed in this specification two forms in which the invention may be embodied, it is to be understood that these forms 10 are shown for the purpose of illustration only, and that the invention is not to be limited to the specific disclosure but may be modified and embodied in various other forms without departing from its spirit. In short, the invention includes all the 15 modifications and embodiments coming within the scope of the following claims.

Having thus fully described the invention, what is claimed as new and for which it is desired to secure Letters Patent, is:

20 1. In a spooling machine, means to support a spool having end plate members and a tubular center member extending between said end plate members, said means including a pair of opposed supports movable relatively to each other, opposed 25 aligned flanges, one at each end of said spool, each of said flanges having an axially directed end portion extending from a face thereof toward the spool to engage the adjacent plate member of the spool to clamp it therebetween, and a spindle extending from its other face, each of said spindles being mounted for free rotation in one of said supports, a pair of conical members mounted one in each spindle and adapted to move axially to enter the ends of said center member to locate the 30 spool concentric to the rotatable flanges, stop means to prevent the entire removal of each of said conical members from said tubular member when the spool is in clamped position between said flanges, and spring means to constantly urge each 40 of said conical members axially into the bore of said tubular member.

2. In a spooling machine, mechanism to clamp and center a spool having end flanges and a central connecting tubular member, said mechanism 45 including a pair of opposed ring-shaped spool-engaging elements, a support for each element, one of said supports being axially movable relatively to the other to clamp a spool between said elements by their engagement with said end 50 flanges, each of said elements being mounted on said support for free rotation and retained against axial movement relatively thereto, a spring-pressed conical member carried by each of said elements and slidably axially relatively thereto to 55 enter the bore in the adjacent end of said tubular member in advance of the engagement of said elements with the spool flanges, and stop means to prevent the entire removal of said conical members from the tubular member when the spool is 60 clamped between said elements.

3. In a spooling machine, mechanism to rotatably support a spool having end flanges driven by a running endless belt in engagement with the material being wound on the periphery of the 65 spool, including a pair of opposed spool flange-engaging plates, a support for each plate, said plates being freely rotatable in said supports and retained against axial movement relatively thereto, one of said supports being axially movable relatively to the other to clamp a spool between said plates by their engagement with said spool end flanges, a conical member carried by and rotated with each of said plates and slidably axially relatively thereto to enter the bore in the adjacent end 70 75

of said tubular member in advance of the engagement of the plate with the spool end flange thereat, stop means to prevent the entire removal of said conical members from the bore of the tubular member when the spool is clamped between said plates, and spring means arranged to constantly urge each of said conical members into the bore of said tubular member to counteract the tendency of the conical members moving axially outwardly from the bore under the influence of the transverse pressure of the running belt on the spool.

4. In a spooling machine wherein a running belt is arranged to drivingly engage the material being wound on the periphery of a spool having end flanges to rotate it, means to counteract the pressure of the belt on the spool and to maintain the axis of the spool substantially parallel to the face of the belt, including a pair of opposed spool flange-engaging plates, a support for each plate, said plates being freely rotatable relatively to their supports, one of said supports being axially movable relatively to the other to clamp a spool between the plates by their engagement with said end flanges, spring-pressed conical members carried by each of said plates and slidably axially relatively thereto to enter and be retained in the bore of the spool, and stop means to prevent the entire removal of said conical members from the bore of the spool when the spool is clamped between said plates.

5. In a spooling machine wherein a running belt is arranged to drivingly engage the material being wound on the periphery of a spool having end flanges, means to counteract the pressure of the belt on the spool and to maintain the axis of the spool substantially parallel to the face of the belt,

including a pair of opposed spool flange-engaging plates, a support for each plate, said plates being freely rotatable relatively to their supports, one of said supports being axially movable relatively to the other to clamp a spool between the plates by their engagement with said end flanges, a conical member carried by each of said plates and slidably axially relatively thereto to enter and be retained in the bore of said spool, stop means to prevent the entire removal of said conical members from the bore of the spool when the latter is clamped between said plates, and spring means acting on said conical members to constantly urge each of said conical members into the bore of said spool to counteract the tendency of the conical members moving axially out of the bore under the influence of the transverse pressure of the running belt on the spool.

6. In a spooling machine for rotating a spool having a pair of end flanges connected by a tubular center member, support means, means to detachably hold said spool on said support means comprising a pair of spring-pressed conical annular plugs slidably carried by said support means and adapted to adjustably enter the ends of said tubular center member to locate said spool concentrically, said support means being adjustable and having means to engage the exterior of said flanges to prevent said spool from tilting with respect to the axis of rotation, and stop means to prevent the entire removal of said plugs from said support means when said spool is removed therefrom.
